UNITED STATES PATENT OFFICE.

WILLIAM M. STARK AND FRANK GEORGE, OF MAYFIELD, KENTUCKY;
SAID GEORGE ASSIGNOR TO SAID STARK.

HAIR-TONIC.

SPECIFICATION forming part of Letters Patent No. 284,918, dated September 11, 1883.

Application filed February 24, 1883. (Specimens.)

To all whom it may concern:

Be it known that we, WILLIAM M. STARK and FRANK GEORGE, of Mayfield, in the county of Graves and State of Kentucky, have invented a new and useful Hair-Restoring Compound, of which the following is a full, clear, and exact description.

To make one pound of the mixture we take six ounces of coal-oil, four ounces of bay-rum, 10 four ounces of alcohol, one-half ounce oil of bergamot, one-fourth ounce of oil of wintergreen, one ounce tincture cantharides, and one-half ounce gum-camphor. These ingredients are to be thoroughly mixed and incorporated, and are then ready to be applied. It should be applied as a wash or lotion to the

hair and scalp, which should be previously cleansed.

As thus applied, the compound has been found very reliable and beneficial in diseases 20 of the hair and scalp.

We claim—

The hair-restoring compound composed of coal-oil, bay-rum, alcohol, oil of bergamot, oil of wintergreen, tincture of cantharides, and 25 camphor, substantially in the proportions specified.

WILLIAM M. STARK.
FRANK GEORGE.
